ARM CHAIR OR THE LIKE

Herbert Ritts, 2221 S. Sepulveda Blvd., Los Angeles, Calif.

Filed Dec. 16, 1963, Ser. No. 77,812

Term of patent 7 years

(Cl. D15—1)

FIGURE 1 is a perspective view of an arm chair or the like, showing my new design;

I claim:

The ornamental design for an arm chair or the like, substantially as shown.
